DEVICE FOR SUSPENDING CLOTHES AND
LIKE ARTICLES

William Hall Blackburn, Lincoln, England

Application October 1, 1946, Serial No. 700,527
In Great Britain October 16, 1945

1 Claim. (Cl. 24—244)

1

This invention relates to devices for suspending clothes, fabrics, carpets, photographic and like prints, operator's drawings used in workshops and like articles.

In drying clothes, which includes in addition to articles of apparel, blankets and fabrics such as bed sheets, in the open air, the edge portions thereof are first of all placed over a clothes-line and then secured by the usual pegs, the limbs of which wedge the material of the articles to bind them firmly to the line. In carrying out this operation and also in removing the pegs, the material is liable to be damaged as the tightly gripping limbs of the pegs slide over it. Silk and like knitted fabrics of delicate texture are invariably damaged in this way as the threads are easily broken with the result that runs or ladders are produced which are difficult to repair so that frequently such articles are rendered unserviceable and are consequently discarded. Thus large numbers of such articles become waste in many cases after little use and a great deal of expense is incurred in replacing them. Furthermore, in drying clothes in a strong wind, particularly clothes having a large surface area such as bed sheets and blankets, the forces imparted to the articles are of such magnitude that the portions of the material that are tightly gripped by the limbs of the pegs tend to be pulled out of that grip so that eventually both the pegs and the articles are displaced or fall from the line and the articles are invariably soiled. Moreover, the continual relative movement that often takes place on the one hand between the limbs of the pegs and the material of the article and on the other hand between the latter and the line before the pegs and the articles are finally displaced from the line, is liable to damage the material.

The object of the present invention is to provide a simple and novel form of suspension device for the above mentioned purposes which will obviate the foregoing disadvantages and in which the articles are adapted to be readily suspended and firmly gripped while suspended and also readily removed therefrom as and when required, always without damaging the material thereof, and, where intended for attachment to a clothes or like line, the device or any desired number thereof may be attached to the line prior to suspending the clothes or the like and said device or devices may remain on the line indefinitely, so that both hands of the user may be free to carry out the suspension of the article or articles of clothing or the like from the device or devices thus facilitating that operation.

2

Throughout the following description similar parts will be designated by similar reference numerals.

Two forms of the suspension device according to the present invention are illustrated in the accompanying drawings, in which:

Figs. 1-3 illustrate one form,
Fig. 1 being a front elevation thereof,
Fig. 2 being a side elevation and
Fig. 3 being a rear elevation, and
Figs. 4-7 illustrate a modified form,
Fig. 4 being a front elevation thereof,
Fig. 5 being a side elevation,
Fig. 6 being a rear elevation, and
Fig. 7 being a plan view.

In carrying out the present invention as illustrated in Figs. 1-3, a wedge-shaped hollow body 1 of rectangular cross-section is cast, preferably, in a single piece and formed of plastic material. The dies for casting the body are constructed so that the cast body will be provided with two opposite side walls 2 and 3 parallel one to the other and the front and rear walls 4 and 5 respectively, converging one towards the other with the wall 5 disposed in a substantially vertical plane and the wall 4 formed with an opening 6 at the lower end for manipulating a wedging roller 7, each of the parallel side walls 2 and 3 having a parallel slot 8 of suitable width extending from the narrow end of the body to a point near the top as illustrated, with the longitudinal edges 9 of said slots flush with the wall 5. Said parallel side walls 2 and 3 are extended outwardly from the body and thickened to form external strengthening ribs 10, 10 beyond the wall 5. The top and bottom ends of the body are left open and the top edge of each of the parallel walls 2 and 3 is shaped to form a hook member 11 which is suitably disposed to permit the device to be suspended with the slots 8 and the adjacent wall 5 with which they are flush, extending substantially vertically.

A steel torsion spring is secured at the upper part of the body cast in the aforesaid form. This spring comprises essentially a coil portion 12 and an arm having a downwardly curved portion 13, an upwardly curved portion 14 and a finger piece 15, and is mounted a suitable distance from the wall 5 about pins 16 and 17 secured in the thicker upper portions 19, 19 of the ribs 10, 10 so that said arm extends over the top of the body approximately centrally between the two hook members 11, 11 and in addition to its main function of securing the body of the device to a line or the like, serves also to prevent displacement

of the roller from the open upper end of the body.

The wedging roller 7 which may be made also of plastic material is adapted to be inserted in the body 1 through the open top and is freely movable therein, the dimensions of the roller 7 being such that the flat ends thereof are disposed closely adjacent the said parallel side walls 2 and 3 but sufficiently clear thereof to permit free movement within the body except at the narrow end where the distance between the two converging walls 4 and 5 is such that the circumferential periphery of the roller 7 will engage both of these walls.

In using the improved suspension device constructed as above for drying clothes and the like for example, the user first of all secures one or more of them to the clothes-line. This is accomplished by first of all depressing the arm 13, 14 of the torsion spring through the finger piece 15 until it reaches a position below the hook-shaped members 11 so that it will be clear of the openings 24 thereof. The user then slips the hook-shaped members onto the line and releases the arm 13, 14 of the torsion spring 12 which thrusts against the underside of the line to press it hard against the upper portion 25 of each of the hook-shaped members 11 and in so doing bends the line upwardly between those members thus locking the device against displacement along the line. Once a number of the devices has been secured to the line as described above, all of them can remain thereon for any desired period or indefinitely. Having secured the device or devices to the line, both hands of the user will then be free to suspend the article or articles of clothing or the like. In carrying out that operation, the user takes a suitable edge portion of the material to be suspended and exerts a light pull thereon in opposite directions while held in both hands in order to flatten that part of the material which is to be inserted in the device. While still held in that way, the material is inserted upwardly in the slots 8 close to the inner surface of the wall 5 when the roller will be raised and also moved forwardly a small amount which is just sufficient to permit the thickness of the material to lie between the inner face of the wall 5 and the cylindrical surface of the roller 7. In some cases and where convenient, the user may displace the roller 7 upwardly and forwardly a small amount by hand when suspending any article of clothing or the like as by inserting his or her thumb or finger through the opening 6 and the lower open end of the body 1. Having inserted the article of clothing or the like in the device in the aforesaid manner, the user removes his or her hands from the former which will then be automatically wedged firmly between the wall 5 and the roller 7, the weight of the clothing or the like and any force applied to it that may tend to remove it from the device serving to wedge it more firmly thereto by the action of the roller 7 which tends to roll downwardly under the action of such forces. It will be observed that in wedging the material of the article of clothing or the like in the device, the roller 7 simply makes contact with it and should any fairly large forces be applied to the material, an extremely small rolling action only can take place between it and the roller as the latter tightens the material in the device, so that damage to the fibres of material of a delicate texture will be obviated.

When it is desired to remove the article of clothing or the like from the device, it is only

necessary for the user to impart a light upward pressure to the roller 7 through the opening 6 and the open lower end of the body when said article of clothing or the like will be released instantly.

It will be understood that when, for example, the device described above is applied to drying clothes having a large surface area, the opposite ends of the material can be suspended initially from two suspension devices secured to the line a comparatively short distance apart when the hands of the user will be free to manipulate either of these two suspension devices in order to release the spring clip or clips thereof and slide one or each of them in turn as required along the line until the article to be dried is exposed over its maximum area when additional intermediate suspension devices may be attached to the line if required.

It will also be understood that in suspending material having a more rigid nature than articles of clothing and other fibrous material, such as thick paper, the user can hold that material in any desired manner and a suitable edge portion of the flat surface thereof simply inserted upwardly in the slots 8 of the device between the inner face of the wall 5 and the roller 7 so that where the surface area is comparatively small the user only needs to employ one hand to suspend the material from the device.

According to a further construction of my improved suspension device as illustrated in Figs. 4-7, a wedge-shaped body 1', constructed of similar form to that particularly described above and formed of plastic material in which it is cast, comprises a vertical wall 5' that is reinforced by ribs 10'. Instead of a spring clip and hook device for securing it to a line, each parallel slot 8' in the two parallel side walls 2' and 3' starting at the bottom with straight edge portions 9' that are flush with the vertical wall 5' and the upper portions of said slots are tapered in an upward direction at 20 to permit the line received in the two parallel slots 8' at the lower end of the device to be wedged in the tapered portion 20 upon thrusting the device downwardly on to the line. The convergent wall 4' which is sloped in respect to the vertical front wall extends for a part of the depth of the body from the lower end and may be terminated at approximately midway of the height of the body at 21, and from that point the adjacent edges of the parallel side walls 2' and 3' are sloped inwardly to the top as indicated at 22 in Fig. 5 to reduce the width of these walls at that point preferably approximately to that at the narrow end of the wedge-shaped body 1'. After inserting the roller 7 through the upper end of the body thus formed, the space between the said sloping edges 22 of the parallel walls, is closed partially or completely by a plate of plastic material 23 provided to prevent the roller escaping through the top of the device.

Although I have particularly described above, two forms of my improved suspension device, I wish it to be understood that I may modify the construction as desired without departing from the characteristic features of my present invention. Furthermore, although I have particularly described the forms of the device constructed of plastic material by casting, they may be cast in any other suitable material, for example, any desired metal such as aluminium, or they may be constructed of wood or like material and the roller may be constructed in any similar materials or of glass or the like.

What I claim is:

A self-contained and removably mountable suspension device of the class described comprising an integral hollow body of rectangular cross-section, open at the upper and lower ends and having flat front and rear walls converging downwardly towards each other with one of said walls extending substantially vertically and the other of said walls extending obliquely thereto from the lower part of the said hollow body for a part of the length thereof and flat side walls parallel one to the other, upstanding slots in the side walls open at their lower ends and tapering upwardly at the upper part of each side wall, the upper tapering portions of said slots serving to support the device from a line like support by the wedging action thereof while the lower portions serve for insertion of the material to be suspended from the device, a roller arranged loosely in said hollow body so that its cylindrical periphery engages throughout its length said oblique wall and wedges the portion of the material inserted through said side wall slots against the said substantially vertically extending wall under the action of gravity and the weight of the suspended 25

article, external ribs on said substantially vertically extending wall to obviate springing of that wall under the wedge action of the roller, and guard means extending between the side walls at the upper part of said body to prevent displacement of the roller from the upper end thereof.
